PSYCHROMETER

Philip G. Magner, Wabash, Ind., assignor to
Minneapolis-Honeywell Regulator Company,
Minneapolis, Minn., a corporation of Delaware

Application January 18, 1935, Serial No. 2,366

7 Claims. (Cl. 73—338)

This invention relates to psychrometers and a sock and wick construction therefor.

Conventional psychrometers as known today, having a wick secured to the lower end of the sock, do not correctly indicate the humidity, especially when the relative humidity is low. The reasons for the inaccurate indications of these psychrometers are that the temperature of the water supplied to the wick, and consequently the 10 temperature of the water supplied to the sock, may be different from the true wet bulb temperature whereby the wet bulb indications may be inaccurate upwardly or downwardly, depending on whether the water temperature is higher or 15 lower than the true wet bulb temperature; that the wick may not supply sufficient water to the sock to be evaporated thereon; and that there may not be a sufficient amount of flow of air past the sock to cause sufficient evaporation.

It is an object of this invention, therefore, to provide a psychrometer that eliminates the above causes for faulty indications.

Inasmuch as it would be impractical to maintain the temperature of the supply of water the 25 same as the true wet bulb temperature, it is an object of this invention to provide means whereby the temperature of the water supplied to the sock is maintained at, or extremely near the true wet bulb temperature regardless of the temperature of the water supply.

More specifically, it is an object of this invention to provide means for passing the air or gas, the relative humidity of which is to be measured, over the wick supplying water to the sock whereby the water in the wick as it is delivered to the 35 sock is at or extremely near to the wet bulb temperature.

In order to secure adequate wetting of the sock at all times it is an object of this invention to 40 provide a novel sock and wick construction.

More specifically, an object of this invention is to provide a unitary or integral sock and wick device wherein there will be a free flow of water from the wick portion to the sock portion of the 45 sock and wick device.

Further, in order to provide an adequate flow of air past the sock and wick, it is an object of this invention to provide a novel air flow controlling means whereby the air, the humidity of 50 which is to be measured, is confined to pass over the sock and wick.

Still further, in order to prevent undue evaporation of the water supply for the wick, it is an object of this invention to prevent contact of the 55 circulated air or gas with the water supply, and

this may be accomplished by the provision of a partition.

Other objects and advantages will become apparent to those skilled in the art by reference to the accompanying specification, claims, and 5 drawing, in which:

Fig. 1 is a vertical sectional view through the psychrometer of this invention;

Fig. 2 is a perspective view of the integral or unitary sock and wick device forming a part of 10 this invention; and

Figs. 3 and 4 are perspective views of the unitary sock and wick device applied to the thermometer of the psychrometer of this invention.

The psychrometer comprises a housing 10 the 15 bottom portion of which is hollowed out as at 11 to receive a bottom plate 12. The bottom plate 12 is appropriately secured to the housing 10 in a fluid tight manner, the housing 10 and the bottom plate 12 forming a reservoir for a water 20 supply for the psychrometer. Water is supplied to the reservoir through a filler opening 13 in the housing 10. The filler opening 13 is normally closed by means of a removable filler cap 14. Suitably secured to the housing 10 and above the 25 level of the water supply in the reservoir is a transverse plate 15 having an opening therein near the center thereof in which is soldered a tube 16.

The upper portion of the housing 10 is provided 30 with an opening 17 in which is placed a cover member 18. The cover member 18 is provided with a vertically extending tubular portion 19 and an elbow portion 20 forming gas or air inlets and outlets, respectively, for the housing or casing 10. A wet bulb thermometer 23 and a dry bulb thermometer 24 are secured and clamped in a clamp member 21 by means of a wing nut 22 cooperating with a screw. The thermometers 23 and 24 are inserted in the inlet tubular portion 19 and are held in place by means of the clamp 21 being inserted in slots 25 in the tubular portion 19. From this it is seen that the thermometers 23 and 24 are maintained directly in the path of the gas or air the relative 45 humidity of which is to be measured.

Secured to the wet bulb thermometer 23 are a sock 26 and a wick 27. The wick 27 extends downwardly from the upper portion of the sock 26 through the tube 16 into the water supply 50 at the bottom of the casing or housing 10.

Referring now to Figs. 2, 3, and 4, the manner of constructing the unitary sock and wick device of this invention is clearly illustrated. An elongated piece of tubular sock material such as rayon 55

tubing is used. Near one end of the tubular sock material an incision 30 is made, as shown in Fig. 2. The wet bulb thermometer 23 is inserted through this incision 30 into the sock material, as shown in Figs. 3 and 4, and the portion of the sock material surrounding the thermometer 23 forms a sock. The remaining and larger portion of the tubular sock material extends downwardly into the water supply to form a wick portion 27 for supplying water to the sock portion 26. The bottom of the sock portion remote from the incision 30 is preferably closed by means of a string or like means 29. The sock and wick are secured to the wet bulb thermometer 23 by means of a string or like means 28.

By constructing the wick and sock in the above described manner an improved operation is obtained in that the sock portion 26 is integral with the wick portion 27 whereby a free flow of water from the wick portion 27 to the sock portion 26 is provided, there being no joints to obstruct the flow of water. Further, by securing the sock and wick construction to the wet bulb thermometer 23 in the manner shown in Figs. 3 and 4 by placing the string or like means 28 around both the sock portion 26 and the wick portion 27, strangulation of the flow of water from the sock portion 26 to the wick portion 27 is prevented since water may flow from the sock portion to the wick portion below the string 28.

Referring now to Fig. 1, it is seen that the wick portion 27 extends downwardly from the upper end of the sock portion 26. By reason of this, the air or gas, the relative humidity of which is to be measured, is passed over both the sock portion 26 and the wick portion 27. If the water supply is warmer than the true wet bulb temperature, this warmer water, as it travels up the wick portion 27 by capillary action, is cooled by evaporation caused by the air or gas passing over the wick portion 27. This evaporation of water in the wick portion 27 causes cooling of the water therein to, or nearly to, the true wet bulb temperature so that water at the correct temperature is supplied to the sock portion 26 by the wick portion 27 regardless of the temperature of the water supply. This construction in effect causes a precooling of the water used for wetting the sock portion 26, whereby accurate indications of humidity may be obtained.

Air or gas is drawn in through the inlet tube 19 of the casing 10 and out through the outlet elbow 20 by means of a fan 31 which is operated by a conventional motor 32. The motor 32 is mounted on a base 33 which is made integral with the casing or housing 10 by means of a web 34. Also integral with the housing 10 is a gas or air funnel 35 which confines the flow of air about the fan 31 to increase the efficiency of operation thereof.

By reason of the transverse plate 15 and the tubular portion 16, the circulating air or gas in the housing 10 is maintained out of contact with the water supply in the reservoir at the bottom of the housing 10 whereby undue evaporation of the water supply by the circulating gas or air is prevented.

By reason of the tubular portion 19 of the cover member 18 the air or gas, the humidity of which is to be measured, is confined for passage over the sock portion 26 and the wick portion 27 which increases the evaporating action in the sock portion 26 to give more accurate wet bulb indications.

From the above it is seen that I have invented a psychrometer of novel construction wherein the water supplied to the sock by the wick is brought

to substantially wet bulb temperature regardless of the temperature of the water supply; wherein the passage of the gas or air past the sock and wick is confined to increase the evaporating action on the sock and wick; wherein undue evaporation of the water supply is eliminated; and wherein free and easy travel of the water from the wick to the sock is accomplished by means of my novel unitary sock and wick device.

While one embodiment of this invention has been shown and described, it is obvious that many modifications may be apparent to one skilled in the art, and consequently this invention is to be limited only by the scope of the appended claims.

I claim as my invention:

1. In a device of the class described, a casing adapted to contain a water supply therein at a lower portion thereof, a gas inlet and a gas outlet in said casing, means for passing a gas the relative humidity of which is to be measured, through said inlet, downwardly through said casing, and said outlet, a thermometer extending in said inlet in the path of flow of the gas, and a sock and wick secured to said thermometer, said wick extending substantially vertically from the upper end of said sock and downwardly into said water supply whereby the gas passes over said sock and said wick to bring the water supplied to said sock by said wick to substantially wet bulb temperature.

2. In a device of the class described, a casing adapted to contain a water supply therein in a lower portion thereof, a gas inlet and a gas outlet in said casing, means for passing a gas, the relative humidity of which is to be measured, through said inlet, downwardly through said casing, and said outlet, a thermometer extending in said inlet in the path of flow of the gas, a sock and wick secured to said thermometer, said wick extending substantially vertically from the upper end of said sock and downwardly into said water supply whereby the gas passes over said sock and said wick to bring the water supplied to said sock by said wick to substantially wet bulb temperature, and a partition in said casing above said water supply having an opening therein through which said wick extends whereby contact of the circulated gas with the water supply is prevented.

3. In combination, a sock and wick construction comprising an elongated piece of tubular sock material having an incision therein, a thermometer extending through said incision into said sock material, the portion of said sock material surrounding said thermometer forming a sock and the remainder of sock material forming a wick, the wick portion of said sock material being doubled back on the sock portion thereof, and means for securing the sock portion to said thermometer and for securing said wick portion in said doubled back relation to said sock portion.

4. In combination, a sock and wick construction comprising an elongated piece of tubular sock material having an incision therein, a thermometer extending through said incision into said sock material, the portion of said sock material surrounding said thermometer forming a sock and the remainder of sock material forming a wick, the wick portion of said sock material being doubled back on the sock portion thereof and secured thereto, means for closing the open end of said sock portion, and means for securing the sock portion to said thermometer.

5. In a device of the class described, a casing adapted to contain a water supply therein in a lower portion thereof, a gas inlet and a gas outlet for said casing in an upper portion thereof, means

- for passing a gas, the relative humidity of which is to be measured, through said inlet, said casing, and said outlet, a thermometer extending in said inlet in the path of flow of the gas and at an angle to the horizontal, a unitary sock and wick device secured to said thermometer by extending said thermometer through an incision in said unitary sock and wick device, said wick portion of said device extending from the upper end of said 5
10 sock portion of said device downwardly into said water supply whereby the gas passes over said sock and wick portions to bring the water supplied to said sock portion by said wick portion to substantially wet bulb temperature, and a partition in said casing above said water supply having an opening 15
20 therein through which said wick portion extends whereby evaporation of said water supply by the 10 circulated gas is substantially prevented.
6. In a device of the class described, a casing adapted to contain a water supply therein in a lower portion thereof, a gas inlet and a gas outlet for said casing in an upper portion thereof, means for passing a gas, the relative humidity of which is to be measured, through said inlet, said casing, and said outlet, a thermometer extending in said inlet in the path of flow of the gas and at an angle to the horizontal, a unitary sock and wick device secured to said thermometer by extending said 15
20
25 thermometer through an incision in said unitary
- sock and wick device, said wick portion of said device extending from the upper end of said sock portion of said device downwardly into said water supply whereby the gas passes over said sock and wick portions to bring the water supplied to said sock portion by said wick portion to substantially wet bulb temperature, and a partition in said casing above said water supply having an opening 10
15
20
25 therein through which said wick portion extends whereby evaporation of said water supply by the circulated gas is substantially prevented.
7. In a device of the class described, a passage for the flow of a gas, the relative humidity of which is to be measured, a thermometer in said passage, a sock and wick secured to said thermometer, and a supply of water for said wick spaced from said sock, said wick extending from the end of said sock farthest from said water into said water over a path through said gas passage, the closest point of the path to the inlet of the 20
25 passage being the end of the sock to which the wick is attached, whereby the gas passes over first the sock and the wick and then the wick alone.

PHILIP G. MAGNER. 25
